Primary Examiner—Dominic Simone*(74) Attorney, Agent, or Firm*—Richard B. Klar(57) CLAIM

A design for an artificial palm tree assembly for a patio table, as shown.

DESCRIPTION

The sole FIGURE is a perspective view of an artificial palm tree assembly having light decoration thereon installed in a patio table, the table shown in broken lines and forming no part of the claimed design.

The elements shown in broken lines are not parts of the design.
